United States Patent Office

Des. 214,411
Patented June 10, 1969

214,411

TIRE

Eric Clifford Bartlett, Birmingham, England, assignor to
The Dunlop Company Limited, Birmingham, England,
a corporation of Great Britain

Filed Mar. 25, 1968, Ser. No. 11,131

Claims priority, application Great Britain Nov. 1, 1967

Term of Patent 14 years

Int. Cl. D12—14

U.S. Cl. D90—20

FIG. 1

FIG. 2

FIG. 3

FIGURE 1 is a perspective view of a tire showing my new design, it being understood that the pattern shown continues through the circumference of the tire, and that the side opposite is the same as the side shown;

FIGURE 2 is a fragmentary top plan view thereof; and FIGURE 3 is a fragmentary perspective view thereof.

I claim:

The ornamental design for a tire, as shown and described.
